 GERMANY

MEANS FOR SPREADING CUT TOBACCO

Application filed July 8, 1929, Serial No. 376,703, and in Germany July 5, 1928.

This invention relates to means for spreading cut tobacco.

In order to take care of the tobacco in tobacco spreaders and to protect the fibres from being torn apart it has been proposed to move a travelling sieve band or the like subjected to suction action past the tobacco supply on which band the tobacco fibres from the hopper settle so as to form a tobacco fleece on the band and on the further movement of the sieve the suction action is interrupted so that a uniform stream of tobacco is delivered in the form of a band by the sieve to a further conveyor.

In order to ensure the separation of the tobacco fleece from the moving sieve band I have already proposed that at the point where the suction action is interrupted a jet should be provided to force compressed air through the openings in the sieve band and blow the tobacco fleece off the sieve band.

For the purpose of simplifying the apparatus, in accordance with the present invention the tobacco fleece formed on the moving sieve band is supported adjacent the delivery point by a moving band or the like impervious to air which removes the tobacco fleece from the suction action. In this manner the use of a compressed air jet is rendered superfluous.

One embodiment of the new device is illustrated in vertical cross section in the accompanying drawing.

Referring to the drawing, the operative flight of the sieve band 5 which travels over the rollers 34, 35 and 36 is under the suction action of the suction box 39 so that tobacco is sucked from the container and fed forward as a tobacco fleece by the sieve band.

The tobacco fibres are straightened by the jet 14 by air under pressure. The brushing roller 16 brings the fleece to the desired thickness. Before the sieve band reaches the rear edge 17 of the suction box the feed band 19 which is guided over the rollers 20 and 21 comes from beneath and rests on the tobacco fleece. The band 19 is of a material which is impervious to air so that the suction action is interrupted adjacent this band. Adjacent the roller 35 the bands 5 and 19 which

are moving at the same speed separate and the tobacco fleece rests under its own weight on the feed band 19 from which it is delivered to the usual grooved conveyor 23.

I claim,

1. Means for spreading cut tobacco comprising in combination with a sieve band subjected to suction action and serving to form a tobacco fleece, an impervious feed band disposed adjacent the delivery point of the sieve band, said impervious band interrupting the suction action adjacent the delivery point of said sieve band, and serving to carry the tobacco fleece out of the range of the suction action exerted on the sieve band.

2. Means for spreading cut tobacco into a fleece comprising in combination, a travelling sieve band, a portion of which is subjected to suction action, means for feeding cut tobacco to said band, means for straightening said cut tobacco as it is picked up by said band, means for regulating the thickness of the fleece carried by said sieve band and means for carrying said fleece out of range of the suction acting through said sieve band, said last named means comprising an impervious feed band disposed closely to the sieve band and overlapping a part of said suction actuated portion of the sieve band adjacent the delivery point of the latter.

3. Means for spreading cut tobacco comprising a travelling sieve band, a portion of which is subjected to suction action, means for feeding cut tobacco to said band, said tobacco being carried by the latter in the form of a fleece and means for delivering said fleece to a further conveyor, said last named means comprising an impervious feed band disposed closely to the sieve band and overlapping a part of the suction actuated portion of the said sieve band adjacent the delivery point of the latter, whereby suction action will be cut off at the overlapped part of said sieve band and said fleece will be carried off the latter by said impervious band.

4. Means for spreading cut tobacco comprising a travelling sieve band, a portion of which is subjected to suction action, means for feeding cut tobacco to said band to be carried by the latter in the form of a fleece,

means for regulating the thickness of said fleece on said band and means for delivering said fleece to a further conveyor, said last named means comprising an impervious feed band disposed closely to the operative flight 5 of said sieve band and overlapping a part of the suction actuated portion of said sieve band adjacent the delivery point of the latter whereby suction action will be cut off at the overlapped part of the sieve band and 10 said fleece will rest on said impervious band and be carried off said sieve band.

5. Means for spreading cut tobacco comprising a travelling perforated element, a portion of which is subjected to suction action, 15 means for feeding cut tobacco to said element, said tobacco being carried by the latter in the form of a fleece and means for delivering said fleece to a further conveyor, said last named means comprising an impervious feed element disposed closely to the perforated element and overlapping a part 20 of the suction actuated portion of said perforated element adjacent the delivery point of the latter, whereby suction will be cut off at the overlapped part of said perforated element and said fleece will be carried off the latter by said impervious element.

Signed at Dresden this 14th day of June,
30 1929.
